(57) **CLAIM**

The ornamental design for a charger, as shown and described.

DESCRIPTION

FIG. 1 is a front perspective view of a charger; FIG. 2 is a front orthogonal view of the charger of FIG. 1; FIG. 3 is a left side orthogonal view of charger of FIG. 1; FIG. 4 is a right side orthogonal view of the charger of FIG. 1; FIG. 5 is of a top orthogonal view of the charger of FIG. 1; FIG. 6 is of a bottom orthogonal view of the charger of FIG. 1; FIG. 7 is a rear orthogonal view of the charger of FIG. 1; FIG. 8 is a rear perspective view of the charger of FIG. 1; FIG. 9 is a front perspective view of a charger; FIG. 10 is a front orthogonal view of the charger of FIG. 9; FIG. 11 is a left side orthogonal view of the charger of FIG. 9; FIG. 12 is a right side orthogonal view of the charger of FIG. 9; FIG. 13 is of a top orthogonal view of the charger of FIG. 9; FIG. 14 is of a bottom orthogonal view of the charger of FIG. 9; FIG. 15 is a rear orthogonal view of the charger of FIG. 9; and, FIG. 16 is a rear perspective view of the charger of FIG. 9. The broken lines present in the drawings are included for the purpose of illustrating portions of the article which form no part of the claimed design.

1 Claim, 12 Drawing Sheets
